UNITED STATES PATENT OFFICE.

GARRET B. OSTERHOUT, OF PROVIDENCE, RHODE ISLAND, ASSIGNOR TO WILLCOX & GIBBS SEWING MACHINE CO., OF NEW YORK, N. Y., A CORPORATION OF NEW YORK.

ROTARY TAKE-UP.

1,134,482.

Specification of Letters Patent.

Patented Apr. 6, 1915.

Application filed September 30, 1913. Serial No. 792,675.

To all whom it may concern:

Be it known that I, GARRET B. OSTERHOUT, of Providence, Rhode Island, have invented a new and useful Improvement in Rotary Take-Ups, which invention is fully set forth in the following specification.

This invention relates to improvements in rotary take-ups, and more especially to the general type of take-up shown in patent to 10 A. A. Merritt, No. 1,041,715, dated October 15, 1912, designed especially for use upon a sewing machine of the character shown in patent to A. A. Merritt, No. 1,041,652, dated October 15, 1912.

15 The object generally is to provide a take-up capable of close and precise adjustment in its action upon the thread, and more particularly to attain just the proper tightening of the needle threads at the instant in the 20 stitch-forming cycle when loops in said threads are slipping off the points of the loopers. This and other advantages are attained by the structure of this invention, the at present preferred embodiment of 25 which is illustrated in the accompanying drawings, wherein—

Figure 1 is a vertical sectional view through a portion of a sewing machine, including a take-up of the present invention 30 turned to such position as to exert its minimum action on the thread; Fig. 2 is a similar view but with the take-up turned to such position as to exert its maximum action on the thread; Fig. 3 is a face view of the take-up partly broken away and sectioned; Fig. 4 is a side view with the outline of the take-up cams dotted; and Fig. 5 comprises a detail view of a compensating spring and a sectional view on line 5—5 of Fig. 2. 40 Figs. 1 to 4 inclusive are on an enlarged scale, while Fig. 5 is drawn to actual size.

10 is a part of the bridge portion of the frame-work of a sewing machine of the type illustrated in the aforesaid Merritt Patent 45 No. 1,041,652; 11 is a bracket mounted on said bridge portion and supporting a thread guide 12 and tension disks 13 for a cross-thread 14. A thread guide 15, tension plates 16 for four needle threads 17, thread guiding hooks 18, one for each of the cross threads 14 and the four needle threads 17, are also mounted on bracket 11.

At 19 there is shown a second set of 50 thread guiding hooks mounted on the bridge portion 10, one for each of the threads re-

spectively, from which hooks the four needle threads 17 pass to thread guiding openings 20 (on the head of the machine, only a portion of which head is shown in Figs. 1 and 2), thence through thread guiding openings 60 21 at the lower end of the needle bar to the four needles 22 respectively. The dotted line 23 in each of Figs. 1 and 2 indicates the approximate position of the upper surface of the throat plate of the machine, these 65 two views, as before stated, showing the relative positions of the parts at different stages of the movement thereof in the stitch-forming cycle.

The parts thus far referred to in the detailed description are substantially the same 70 in construction as corresponding parts in the said Merritt Patent No. 1,041,652, above mentioned.

25 is a horizontal take-up shaft suitably 75 journaled in the frame-work of the machine. It is shown in this particular instance as carrying a double take-up fixed upon the shaft by a set-screw 26. One portion 27 of said take-up, between flanges, disks or 80 plates 28 and 29, is adapted to act upon the cross thread 14, and the other portion 30 of said take-up, between the flanges or disks 29 and 31, is adapted to act upon the four needle threads 17. The threads pass over 85 the take-up between the thread guiding hooks 18 and 19, before mentioned. The surface of the part 27 of the take-up which acts upon the cross-thread is cam-shape in outline and positioned eccentric to the 90 shaft 25, as shown in dotted lines in Fig. 4. It is preferred to make the double take-up in three parts, one part comprising flanges or plates 28, 29 and 31 and cam 34, cast or formed in one piece, and having a hub adjacent plate 28 through which a screw 26 passes. Cam 34 is fixed and has a flattened 95 surface 36. The second part of the double take-up is a crescent-shaped member 32 which is U-shape on its inner face to engage 100 a hub 33 and to allow of its withdrawal over hub 33, as clearly shown in Figs. 3 and 4. The outer edge of the crescent-shaped member 32 and that portion of the surface of the hub 33 between the ends of 105 said member, present together a continuous cam-like surface adapted to act upon the cross-thread 14 with the necessary take-up action. A screw 50 passes loosely through plate 28, the arc-shaped slot 51 in crescent-

95

100

105

110

shaped member 32, and engages a threaded opening in plate 29. This screw adjustably secures the member 32 in place, so that it may be independently turned to relatively 5 adjust or change the time of action of the take-up surfaces which act upon the cross-thread. The third part of the double take-up comprises an adjustable extension 35 of the cam 34; said part 35 has a nose 39 at 10 one end and a foot 39' at its other end contacting the flat face 36. A screw 37 countersunk in part 35 secures it to part 34. An adjusting screw 38 countersunk in a screw-threaded opening in the adjustable cam part 15 35 bears at its inner projecting end against the end of the surface 36 of part 34. When it is desired to adjust the take-up to give greater action upon the needle-threads, the set-screw 37 is first loosened and the adjusting screw 38 then turned to move the adjustable cam part 35 outwardly to the desired extent, and the set-screw 37 then again tightened. To lessen the action of the take-up 20 upon the needle-threads, this manipulation 25 of the parts is reversed.

In conjunction with the take-up, there is provided for action upon the needle-threads a compensating spring 40 which is bent at one end to fit a similarly shaped depression 30 41 (Fig. 5) in a flat surface 42 of the bracket 11, against which face the thread guide 15 seats and is held by a screw 43 passing through opening 44 at the inner end of spring 40 and into a screw-threaded opening 45 in the surface 42 of the bracket. The spring 40 extends downwardly and at its lower extremity has a right angled approximately horizontal extension 46 lying across the four needle-threads 17 between the guide 40 hooks 18 and the take-up. This compensating 45 spring acts to take up slack in the needle-threads, more particularly when the adjustable needle-thread take-up is moving from its position of maximum action on the threads to its position of minimum action, during which period it is releasing the threads.

In the position of the parts shown in Fig. 1, the needles 22 are about to begin their 50 ascending movement and the needle-thread

part of the take-up is in its position of minimum action upon said threads. In Fig. 2, the needles 22 are at about the limit of their upward movement and the take-up is in its position of maximum action upon the 55 threads.

What I claim is:—

1. A rotary take-up having in its surface which contacts with the thread a fixed cam-like part followed by an adjustable portion 60 constituting a continuation of said cam-like part.

2. A rotary take-up having in its surface which acts upon the thread, a fixed section and a movable section adjustable in its position to increase or decrease the take-up 65 action upon the thread one of said sections following the other as an approximate continuation thereof.

3. A rotary take-up having in its surface 70 which acts upon the thread a fixed section and a movable section adjustable radially to the axis of rotation to vary its take-up action upon the thread, one of said sections following the other as an approximate continuation thereof.

4. The combination of thread tensioning means; a rotary take-up for acting upon the thread after the latter has passed the thread tensioning means; and a take-up 80 spring separate from the rotary take-up and acting on the thread at one side of said rotary take-up.

5. The combination of thread tensioning means; a rotary take-up for acting upon the thread after the latter has passed the thread tensioning means; and a take-up 85 spring separate from the rotary take-up and acting on the thread at one side of said rotary take-up and adapted to take up slack 90 thread when the rotary take-up is moving from its position of maximum action to its position of minimum action upon the thread.

In testimony whereof I have signed this specification in the presence of two subscribers. 95
